DESIGN FOR A LAWN SPRINKLER

James V. Walsh, Kenmore, N. Y.

Application September 29, 1944, Serial No. 115,514

Term of patent 14 years

(Cl. D91—1)

To all whom it may concern:

Be it known that I, James V. Walsh, a citizen of the United States, residing at Kenmore, in the county of Erie and State of New York, have invented a new, original, and ornamental Design for a Lawn Sprinkler, of which the following is a specification, reference being had to the accompanying drawing, forming part thereof.

In the drawing:

Fig. 1 is a perspective view of a lawn sprinkler showing my new design.

Fig. 2 is an elevational view thereof, the opposite side of the vertical stem and umbrella-like top being substantially the same; and

Fig. 3 is a bottom plan view thereof.

The drawing is lined for contrasting colors.

I claim:

The ornamental design for a lawn sprinkler, as shown and described.

JAMES V. WALSH.
